DESIGN FOR A TRIMMING FOR DRESSES, SUITS, AND COATS

Victor J. Sigoda, Brooklyn, N. Y., assignor to Manhattan Scalloping & Embroidery Works, New York, N. Y., a firm composed of Julius Markowitz and Mark Sigoda

Application December 17, 1936, Serial No. 66,599

Term of patent 14 years

To all whom it may concern:

Be it known that I, Victor J. Sigoda, a citizen of the United States and a resident of Brooklyn, county of Kings, and State of New York, have invented a new, original, and ornamental Design for a Trimming for Dresses, Suits, and Coats, of which the following is a specification, reference being had to the accompanying drawing, forming a part thereof.

It is characteristic of my design that portions of the top nodes of the trimming are covered by an ornamental fillet of fabric.

In the accompanying drawing:

I claim:

The ornamental design for a trimming for dresses, suits and coats, substantially as shown and described.

VICTOR J. SIGODA.
